UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE OF SPOONS, FORKS, OR SIMILAR ARTICLES.

● 40,519.

Specification for Design.

Patented Feb. 22, 1910.

Application filed December 23, 1909. Serial No. 534,744. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for the Handle of a Spoon, Fork, or Similar Article, reference being had to the accompanying drawings.

Figure 1 is a view of the obverse side of

the handle, showing my design. Fig. 2 is a view of the reverse side of the same.

I claim—

The ornamental design for the handle of a spoon, fork or similar article, as shown.

WILLIAM C. CODMAN.
